(57) **CLAIM**

The ornamental design for serrated postage label, as shown
and described.

DESCRIPTION

FIG. 1 is a top plan view of a serrated postage label showing
my new design;

FIG. 2 is a front elevational view thereof, the rear elevational
view being identical;

FIG. 3 is a right side elevational view thereof, the left side
elevational view being identical;

FIG. 4 is a bottom plan view thereof;

FIG. 5 is an enlarged portion of the microprinting vertically
disposed on both the right and left sides of the top plan view
of FIG. 1 shown separately for ease of illustration; and,

FIG. 6 is a top plan view thereof.

The broken line showing of the serrated postage labels in
FIG. 6 is for illustrative purposes only and forms no part of
the claimed design.
